Assistant Examiner — Brett Miller

(57) **CLAIM**

The ornamental design for a food chopper gasket, as shown and described.

DESCRIPTION

FIG. 1 is a perspective view of an food chopper gasket showing the design in the context of a closed food copper; FIG. 2 is a perspective view thereof in the environmental perspective of an open food chopper;

FIG. 3 is a to plan view thereof;

FIG. 4 is a bottom plan view thereof;

FIG. 5 is a left elevational view thereof;

FIG. 6 is a right elevational view thereof;

FIG. 7 is a front elevational view thereof; and,

FIG. 8 is a rear elevational view thereof.

The broken lines depict environmental structure and form no part of the claimed design.

1 Claim, 5 Drawing Sheets
